UNITED STATES PATENT OFFICE.

MILTON C. LENOIR, OF LOMBARD, ILLINOIS, ASSIGNEE TO THE P & M COMPANY, OF CHICAGO, ILLINOIS, A CORPORATION OF ILLINOIS.

RAIL ANCHOR.

Application filed December 30, 1926. Serial No. 158,060.

My invention relates to rail anchors and especially to improvements in anchor devices of the character which is adapted to grip one flange only of a rail base.

5 The principal object of the invention is to provide in a one-piece anchor device of the above general character certain new and improved constructions whereby the anchor device may be easily applied to its operative 10 position and which will be retained in its applied position by the resilient qualities of the members and the interlocking engagement of portions of the device with grooves formed in the rail, at an angle to each 15 other, during the application of the device to the rail.

Another object is to provide a device of the above character which is so formed that it may be applied to the rail by movement 20 of the anchor about a vertical axis, and which may be so positioned against a cross tie and driven transversely of the rail as to move a portion of the anchor longitudinally of the rail to produce a groove which 25 cooperates with a part of the anchor to lock the anchor device in its applied position.

A further and more specific object is to 30 provide a rail anchor with jaws which grip the top and bottom surfaces of a rail base adjacent the cross tie and with a biting shackle grip and to provide in an anchor of this general character, rail grooving portions which lock the anchor in its applied 35 position.

The invention has for further objects the new and improved constructions hereinafter described and claimed for carrying out the above stated objects and such other objects 40 as will appear from the following description of the embodiments of the invention shown in the accompanying drawings.

In the drawings:

Fig. 1 is a plan view of a railroad rail 45 and cross tie showing a rail anchor device constructed in accordance with my invention in a position which it assumes during its application to a rail.

Fig. 2 is a view similar to Fig. 1, but 50 showing the rail anchor in its applied position.

Fig. 3 is a cross section through the rail on line 3-3 of Fig. 2 and showing the end portion of the anchor in elevation.

55 Fig. 4 is a side view, in elevation, of the

rail anchor in its applied position, a portion of the rail flange being broken away so as to illustrate the manner in which portions of the anchor take a biting hold on the rail base.

Fig. 5 is a plan view of the rail base illustrating the character of grooves formed in the base flange of the rail during the application of the anchor to its applied position.

Fig. 6 is a cross-sectional view taken on line 6-6 of Fig. 2.

Fig. 7 is a view in perspective of the anchor shown in the preceding figures.

Figs. 8 and 9 are views similar to Figs. 1 and 2, but showing a modified embodiment 70 of the anchor device.

Figs. 10 and 11 are views similar to Fig. 3 and 4 showing the modified anchor in its applied position on the rail.

Fig. 12 is an inverted plan view of the rail 75 base illustrating the character of grooves formed in the rail base during the application of the modified anchor.

Fig. 13 is a sectional view taken on line 13-13 of Fig. 9.

Fig. 14 is a view in perspective of the modified embodiment shown in Figs. 8 to 80 13 inclusive, and

Figs. 15, 16 and 17 are views similar to Figs. 9, 10 and 11 but show the anchor device applied in an inverted position with respect to the position illustrated in Figs. 9, 10 and 11.

Referring first to Figs. 1 to 7 inclusive of the drawings wherein I have shown the construction and manner of applying one embodiment of my invention. This embodiment consists of a spring metal plate recessed to provide upper and lower jaws 10 and 11 and to provide relatively long upper and lower resilient arm portions 12 and 13. The jaws are formed, preferably, though not necessarily, parallel to each other so that the lower jaw will bear for the major portion of its length, against the horizontal bottom surface 14 of the rail base and so that the upper jaw will bear at its end only against the inclined top surface 15 of the rail base. The portion of the recess 16 providing the jaws 10 and 11 is of such size that the jaws are spread apart slightly when the device is driven to its applied position and so that the jaws take a biting hold on the top and bottom surfaces, respectively, of the rail base.

The arm portions 12 and 13 are bent to stand, preferably, at right angles to the jaws 10 and 11 of the device. The space between the extremities of the arms is normally less than the thickness of the rail base so that the arms are spread apart slightly when in their applied position. The arms are formed also to engage at their outer ends only with the rail base. The rail engaging ends of these arms are curved longitudinally of the arms, as indicated by the reference numerals 17 and are bent outwardly at 18, as shown best in Figs. 3 and 7, so that the sharp inner corners 19 and 20 of the arms normally extend at an angle to the adjacent longitudinal edge of the rail base. The sharp corners of the arms bite into the top and bottom surfaces of the rail base, as indicated in Figs. 3 and 4, and thereby form substantially V-shaped grooves 21 which extend at an angle to the longitudinal edge of the rail base.

In applying the anchor to a rail, the ends of the arms 12 and 13 are fitted over one edge of the rail base so that the arms extend at an angle to the rail and so that the jaws 10 and 11 extend at an angle to the vertical face of the adjacent cross tie 22, substantially as indicated in Fig. 1. The tie-abutting portion of the anchor is then driven transversely of the rail, from the position shown in Fig. 1 to the position indicated in Fig. 2, in which the jaws 10 and 11 are driven into spring-gripping engagement with the top and bottom surfaces of the rail base and assume a position perpendicular to the bottom surface of the rail base and at right angles to the adjacent longitudinal edge of said base. During the movement of the anchor to its applied position, the pressure exerted against the tie forces the extremities of the arms longitudinally of the rail in a direction away from the cross tie 22, so as to form grooves 21-21^a in the top and bottom surfaces of the base of the rail. The transverse movement of the jaw end of the anchor forces the upper jaw upon the inclined top surface of the rail base and produces a groove therein, substantially as shown in Figs. 5 and 6, by the reference character 24. The grooves 21-21^a and the groove 24, it will be seen, extend at an angle to each other, and thereby resist transverse movement of the anchor in a direction to loosen the grip on the rail base. The spring pressure exerted by the arms 12 and 13 is substantially equal on the top and bottom surfaces of the rail base. The jaw portions of the anchor are maintained, therefore, in a position substantially perpendicular to the bottom surface of the rail base.

The anchor may be applied to either flange of the rail in the position corresponding to that shown in Figs. 1 to 7 inclusive, or it may be applied in an inverted position to

either side of the rail. It will be seen, therefore, that the jaw 10 and the arm 12, designated in the above figures as the upper jaw and arm, respectively, will be the lower jaw and arm, when the anchor is applied in an inverted position.

In Figs. 8 to 14 inclusive, I have shown a modified construction, in which an arm 13^a, similar to one of the angularly disposed arms shown in the preceding figures extends longitudinally of and bears against the rail base. This arm is preferably, though not necessarily, so disposed as to form an acute angle with the jaw member. The upper and lower jaws 10^a, 11^a of the modification normally converge toward the outer ends, so that the said extremities of the jaws, when embedded in the rail base, shown in Fig. 13, will form grooves which increase in depth in a direction away from the adjacent edge of the rail base. The extremity of the arm 13^a is formed in the same manner as the arms illustrated in Figs. 1 to 7 inclusive, so that the sharp edge 20^a will engage one surface of the rail base and forms a groove therein at an angle to the longitudinal edge of the rail base. The said edge 20^a is preferably so disposed with relation to the jaws 10^a-11^a as to cause the jaw portion of the anchor to rock longitudinally of the rail (Fig. 11) when the edge 20^a is forced into engagement with the bottom surface of the rail base.

In applying the modified embodiment, the anchor is fitted on one edge of the rail base in the position indicated in Fig. 8. In this position of the anchor, the upper jaw 10^a is hooked over the upper longitudinal edge of the rail base. The anchor is then driven transversely of the rail to the position shown in Fig. 9. The pressure exerted by the lower jaw portion 11^a against the vertical face of the adjacent cross tie 22^a forces the angularly disposed arm 13^a longitudinally of the rail in a direction away from the cross tie and causes the sharp corner 20^a of the arm to bite into the bottom surface of the rail base in a manner to form a groove substantially as indicated in Fig. 12 by the reference character 25. This longitudinal movement of the arm 13^a is produced by the pressure of the jaw portion of the anchor against the tie, during the movement of the device into its operative position, that is to say, from the angular position shown in Fig. 8, to the applied position shown in Fig. 9. The spring pressure exerted against the bottom surface of the rail base by the arm 13^a tends to rock the jaw portion about a horizontal axis so as to effect a shackle grip on the top and bottom surfaces of the rail base, as indicated in Fig. 11. This rocking movement of the jaw portion moves the outer corner 26 of the jaw 10^a and the corner 27 of the jaw portion 11^a into biting engagement

with the top and bottom surfaces of the rail base so as to form therein the triangular shaped grooves 26^a—27^a indicated in Fig. 12.

With the anchor applied in the manner indicated in Figs. 8 to 13 inclusive, the creeping pressure of the rail forces the lower portion of the anchor against the adjacent cross tie and thereby tends to increase the biting hold of the end portion of the arm 13^a with 10 the under surface of the rail base. The device, however, is capable of being inverted and applied to the rail in the same manner as that indicated in connection with the embodiment illustrated in Figs. 1 to 7 inclusive. 15 When the modified form of anchor is inverted and applied to the rail, the arm 13^a takes a biting hold on the top inclined surface of the rail base and therefore tends to tilt the anchor in a direction opposite to that indicated in Fig. 11. When the anchor is tilted in the above manner, the creeping pressure of the rail in a direction toward the cross-tie 22^a tends to increase the shackle hold of the jaws 10^a and 11^a on the top and 20 bottom surfaces of the rail base. The triangular grooves 26^a—27^a, increasing in depth toward the center of the rail, provide a lock which prevents the device from moving outwardly with relation to the edge of the rail base. The angular position of the groove 25 also lends itself to maintaining the anchor on the rail base by resisting movement of the anchor in a direction tending to loosen 25 its grip on the rail.

I claim:

1. A rail anchor comprising a member formed with jaws adapted to be driven into engagement with one flange of a rail base, and a spring arm extending outwardly from 40 the jaw portion of said device and adapted to bear with spring pressure against the said base flange.

2. A rail anchor comprising a member formed with jaws adapted to be driven into biting engagement with one flange of a rail base, and a spring arm extending outwardly from the jaw portion of said device and formed with a sharp corner portion adapted to bite into said rail base.

3. A rail anchor comprising a member formed with jaws adapted to be driven into biting engagement with one flange of a rail base, and a spring arm extending outwardly from the jaw portion of said device and formed with a sharp corner portion adapted to bite into said rail base to form a groove extending at an angle to the adjacent longitudinal edge of the rail base.

4. A rail anchor comprising a member formed with jaws adapted to be driven into biting engagement with one flange of a rail base, and a spring arm extending outwardly from the jaw portion of said device and formed with a sharp corner portion adapted to bite into the said rail base to form a

groove extending at an angle to the grooves formed by the biting grip of said jaws so as to resist movement outwardly with relation to the edge of the rail base.

5. A rail anchor comprising a member 70 formed with jaws, one of which bears flat against the bottom surface of the rail base, and the other of which bears at its end only against the top surface of the rail base, and a spring arm extending outwardly from the 75 jaw portion of said device and formed with a sharp corner portion adapted to bite into said rail base to form a groove extending at an angle to the grooves formed by the biting grip of said jaws so as to resist movement 80 outwardly with relation to the edge of the rail base.

6. A rail anchor comprising a member formed with jaws for engaging the top and bottom surfaces of the base flange of a rail 85 at one side of the rail and formed with a spring arm extending longitudinally of the rail, the end portion of which arm is bent so that the corner portion thereof bears against the said base flange. 90

7. A rail anchor comprising a member formed with jaws for engaging the top and bottom surfaces of the base flange of a rail at one side of the rail and formed with a 95 spring arm extending longitudinally of the rail, the end portion of the arm being bent longitudinally and transversely of the arm so that a corner portion thereof bears against the rail base at an angle to the adjacent edge of said base. 100

8. A rail anchor comprising a member formed with jaws for engaging the top and bottom surfaces of the base flange of a rail at one side of the rail and formed with a 105 spring arm extending longitudinally of the rail, the said arm being formed at its extremity with a sharp edge portion adapted to bite into the rail base at an angle to the adjacent edge of said base.

9. A rail anchor comprising a member formed with jaws adapted to be driven into gripping engagement with the top and bottom surfaces of a rail base and formed with a spring arm having a biting engagement with the rail base; said jaws and arm being 110 disposed with relation to each other, whereby the anchor may be applied to either side of the rail base in various positions.

10. A rail anchor comprising a member formed with jaws which converge toward 120 their ends and are adapted to be driven into gripping engagement with the top and bottom surfaces of a rail base and a spring arm having a biting engagement with the rail base; the said jaws and arm being disposed 125 with relation to each other whereby the anchor may be applied to either side of a rail base in various positions.

11. A rail anchor comprising a member formed with jaws adapted to be driven into 130

gripping engagement with the top and bottom surfaces of the rail base and formed with spaced spring arms extending longitudinally of the rail and adapted to be driven into gripping engagement with the top and bottom surfaces of the rail base, the distance between the extremities of said arms being normally insufficient to receive a rail base therein, whereby the said arms are spread apart and exert spring pressure on the top and bottom surfaces of the rail base when the anchor is in its applied position.

12. A rail anchor comprising a clip member formed with jaws adapted to be driven into biting engagement with the top and bottom surfaces of the rail base at one side of the rail, a spring arm extending longitudinally of the rail from each of said jaws, and the said arms being formed at their ends with biting edges which extend at an angle to the adjacent edge of the rail base.

13. A rail anchor comprising a clip member formed with jaws adapted to be driven into biting engagement with the top and bottom surfaces of the rail base at one side of the rail, a spring arm extending longitudinally of the rail from each of said jaws, the rail engaging portions of said arms being bent longitudinally and transversely of the arms, whereby the sharp longitudinal edge of each arm engages the rail base at an angle to the longitudinal edge of said base.

14. A rail anchor consisting of a clip recessed to provide jaws for gripping the top and bottom surfaces of a rail base at one side only of a rail and formed with an arm

extending longitudinally of the rail and provided at its extremity with a sharp edge portion adapted to take a biting hold on the rail base and adapted to be forced longitudinally of the rail by the force applied in driving the jaw portion home.

15. A rail anchor consisting of a clip recessed to provide jaws for gripping the top and bottom surfaces of a rail base at one side only of the rail and formed with an arm extending longitudinally of the rail and provided at its extremity with a sharp edge portion adapted to take a biting hold on the rail base; the said anchor being adapted to be positioned against a cross tie with the arm and jaw portion of the device engaging the rail base at an angle to the longitudinal edge thereof, whereby movement of the jaw portion to its applied position exerts force against said tie to force the arm longitudinally of the rail.

16. A rail anchor consisting of a clip recessed to provide jaws for gripping the top and bottom surfaces of a rail base at one side only of a rail and formed with angularly disposed arms extending longitudinally of the rail and provided at their extremities with sharp edge portions adapted to grip said top and bottom surfaces of said base, the said anchor being adapted to be positioned against a cross tie with said arms and jaws engaging the rail base at an angle to the longitudinal edge thereof, whereby movement of the jaws to their applied positions exerts force against said tie to force the arms longitudinally of the rail.

MILTON C. LENOIR.
